UNITED STATES PATENT OFFICE.

ABBOTT A. KAUFFMAN, OF BROOKLYN, NEW YORK.

BRIDGE TOOTH AND LOCK-IN BACKING.

Application filed June 21, 1923. Serial No. 646,862.

To all whom it may concern:

Be it known that I, ABBOTT A. KAUFFMAN, a citizen of the United States, and a resident of the city of New York, borough of Brooklyn, in the county of Kings and State of New York, have invented a new and Improved Bridge Tooth and Lock-In Backing, of which the following is a full, clear, and exact description.

10 This invention has relation to dental bridgework and has particular reference to a bridge tooth and lock-in backing.

The present invention contemplates an improvement in the mode of attachment of 15 the bridge tooth to the bridge whereby the tooth is more firmly united with the bridge, but, is nevertheless capable of ready removal therefrom in event of its breakage and the necessity of replacement.

20 As a further object the invention contemplates a bridge for anchoring a bridge tooth to the abutment teeth, which also constitute a backing for the bridge tooth and which is concealed from view when in place.

25 As a still further object the invention contemplates a bridge tooth designed to include a porcelain tip, and where required an integral root in the original baking.

The invention furthermore comprehends 30 a bridge tooth and bridge which is comparatively simple in its construction, inexpensive to produce and install and highly efficient in its purpose.

With the above received and other objects in view, the invention resides in the novel construction set forth in the following specification, particularly pointed out in the appended claims and illustrated in the accompanying drawings, it being understood 40 that the right is reserved to embodiments other than those actually illustrated herein to the full extent indicated by the general meaning of the terms in which the claims are expressed.

45 In the drawings—

Figure 1 is a rear view of the bridge tooth in place.

Fig. 2 is an enlarged vertical sectional view through the same taken approximately 50 on the line 2—2 of Fig. 1.

Fig. 3 is a horizontal sectional view taken approximately on the line 3—3 of Fig. 1.

Fig. 4 is a perspective view of the bridge tooth alone.

55 Fig. 5 is a similar view of the bridge alone.

Referring to the drawings by characters of reference, A designates a section of the gum and B the abutment teeth between which the artificial bridge tooth is adapted to be arranged. The bridge tooth constituting a part of the invention designated generally by the reference character 10 is provided with a wide peripheral recess 11 which extends around the lingual or rear of the tooth and around the mesial and distal sides of the tooth. The tooth may be provided with or without an integral root 12, if desired, which is designed to seat in the socket of the root of the original tooth. The 70 bridge tooth 10 is further provided with a horizontal bore 13 which extends inwardly from the rear of the tooth and terminates short of the front or buccal side thereof. A vertical bore 14 extends inwardly from the outer end of the tooth and intersects the horizontal bore 13. The bore 13 communicates at its outer end with the recess 11. The bridge member which also constitutes a part of the invention and is designated generally by the reference character 16 is of substantially arcuate formation to snugly fit the recess 11 whereby to embrace the bridge tooth and form a backing therefor. From the central inner portion of the bridge member a tongue 17 conforming substantially to the configuration of the horizontal recess 13 is provided and the free inner end of the tongue 17 is formed with an interiorly threaded vertical opening 18. The opposite sides of the bridge 16 are suitably anchored to the abutment teeth B by soldering the same to an inlay or crown 19 on the abutment teeth or in any other suitable manner, the form of connection between the sides of the bridge member and the abutment teeth constitute no part of the invention. A screw consisting of a shank 20 having a threaded end 21 and a kerfed end 22 is inserted in the vertical bore 14 after the 100 bridge member 16 is applied to the bridge tooth. The threaded end 21 of the shank is engaged within the threaded opening 18 of the tongue.

From the foregoing construction and arrangement it will be seen that a bridge tooth and bridge has been provided which are firmly united with each other and in which the bridge member constitutes a backing for the bridge tooth. The tooth will preferably be of porcelain made in all of the necessary shades and molds and will include

in its original baking a porcelain tip and where required an integral root. It thus follows that the expensive operation of baking on a porcelain tip is eliminated and the bridge tooth will be substantially anchored to the bridge member.

I claim:

1. A bridge tooth and a bridge member embracing the rear and side faces of said bridge tooth, said bridge member provided with anchoring means for connecting the same with the abutment teeth, means extending inwardly from the bridge member into the bridge tooth, and an anchoring member 15 extending through the outer end of the bridge tooth and intersecting said means for establishing a connection between the inner end of said means and the bridge tooth.

2. A bridge tooth having intersecting vertical and horizontal bores and a bridge member countersunk in the rear and side por-

tions of the periphery of the tooth, said bridge member provided with a tongue extending into the horizontal bore, and means extending into the vertical bore and inter- 25 engaging the tongue.

3. A bridge tooth having a peripheral recess in the sides and rear faces of the tooth and having bores extending inwardly from the outer end and rear side of the tooth, said 30 bores intersecting each other at their inner ends and an arcuate bridge member adapted to be anchored to the abutment teeth and fitting into one of said recesses, a tongue having a threaded aperture in its inner end 35 carried by the bridge member and extending into one of the recesses with the threaded aperture aligning with the other recess, and a retaining screw inserted in the other recess and threadedly engaging the threaded aperture in the tongue.

ABBOTT A. KAUFFMAN.
